BLACKBOARD AND IMPROVED PROCESS OF
MAKING THE SAME

Ralph W. Shenton, Slaterdale, Pa.

Application June 27, 1938, Serial No. 215,998

10 Claims. (Cl. 35—63)

My invention relates to improved blackboards and to improved processes of making the same, and this application for patent thereon is a continuation in part of my pending application Serial No. 110,887. Particularly, the invention relates to blackboards having a base or body member of suitable material, such as plywood, which serves as a backing-support for a facing of slate veneer utilized as the writing surface. By "blackboards" I mean the various articles which have a natural slate writing surface, such as the well known school slates, school blackboards, conference blackboards, bulletin boards, drafting boards, etc. By "slate veneer" I mean a layer of natural slate smoothly finished which is thinner than has been considered practicable in the past for any sheet of machined or polished slate. The slate sheet which I term "veneer" does not exceed one-sixteenth inch thickness and, in the most usual adaptations of my invention, is of a thickness of the order of one-thirty-second inch.

It is well known that blackboards, bulletin boards, conference boards, school slates, and analogous articles are commonly made of natural slate. Natural slate has a surface texture which is particularly adaptable to highly satisfactory blackboard surfaces. It is well known that it has definite advantages and utility over all other known materials for this purpose. Numerous artificial substitutes, and coatings upon foundation bases, have been tried as blackboard surfaces, without being found to be as successful or useful as natural slate. However, natural slate is a material which easily fractures and breaks. Due to its peculiar composition, it withstands without injury only very slight stresses of certain nature. Furthermore, natural slate is a comparatively heavy material and thus involves considerable labor in handling and high charges for transportation. The use of slate for blackboards involves considerable difficulty in distributing and mounting the boards because of the great weight of the slate, and the liability of breakage. Also, slate is quite a costly material, and its supply in many parts of the country is limited. Thus, the cost of a suitable supply to such parts of the country is prohibitive, particularly when the transportation charges thereto are taken into account. My invention is designed to eliminate to a large extent the aforesaid disadvantages in the use of natural slate for blackboards, and make natural slate for this purpose practicably available.

For use in blackboards it has been necessary to have natural slate of from one-eighth inch thick-

ness up, depending upon the size of the blackboard. My invention is designed to provide an efficient and wholly satisfactory blackboard having a natural slate writing surface by the use of a natural slate veneer for the writing surface, of a final thickness not exceeding one-sixteenth inch, and preferably of a final thickness of the order of one-thirty-second inch. Slate veneer of this character is utilized by me as a writing surface upon a suitable backing-support, such as plywood. This veneer thickness is obtained by machining down thin sheets securely held to a flat base which acts as chuck. The blackboard when fully completed comprises the slate veneer secured, preferably cemented, to a backing-support.

In producing my improved slate veneer, I substantially discard all the slate, with the exception of a machined surface, and then build up the necessary backing-support so that the final product possesses the characteristics of the backing-support with the exception of the natural slate writing surface which is preserved. In fact, only enough slate is preserved to insure that the writing surface will not be worn through by scratching; for instance, when rehoning the slate writing surface. This veneer thinness of the slate becomes evident as the thinness passes below one-sixteenth inch and reaches its practicable limit at about one-thirty-second inch. Such a thinness in the slate veneer results in its losing its dominant characteristics of a stone, such as its weight and rigidity, and the peculiar susceptibility of slate to cracking and splitting, so that there is preserved of the natural slate qualities only its superior quality as a writing surface. The combination of the veneer and its backing-support has the dominant characteristics of the backing material, such as lightness, toughness, and reasonable subjection to bending and warping. This resultant product is subject to carpentering by ordinary carpenter's tools and can be supported by any suitable support by being nailed thereto. The veneer facing is amenable to bending and warping and follows the backing-support when the latter is bent or warped and consistently conforms to all portions thereof, so that at all times the veneer facing hugs its backing-support. At the veneer thinness, the slate has become readily pliable, and the bonded joint between the facing and the support is subjected to no serious mechanical stress by the bending or warping of the backing-support.

In the production of my improved blackboards, I first split the rough natural block into sheets

as thin as can be practicably produced by slate-splitting operations. Then I produce the thinness, which I term a "veneer", by machining the thin split sheet while this thin sheet is securely held to a flat backing which serves as a chuck for the machining, and any desired polishing, thus rendering possible the practicable finishing of the thin sheet down to the thinness which I term "veneer".

10 The annexed drawing and the following description set forth in detail certain means constituting my improved blackboard, and certain improved processes of making the same, such disclosed means constituting, however, only a few 15 of the various forms in which the improved blackboard may be embodied, and only a few of the various series of steps by which the improved processes may be worked.

In said annexed drawing:

20 Figure 1 is a face view of a blackboard embodying my invention nailed to a suitable support such as a building wall;

Figure 2 is a perspective of a conference blackboard embodying my invention, the same being 25 pivotally mounted in a suitable supporting standard;

Figure 3 is a fragmentary vertical section, upon a two-for-one scale, taken in the plane indicated by the line 3—3, Figure 2;

30 Figure 4 is a side elevation of the conference board shown in Figure 2, the view being taken from the side opposite that from which Figure 2 is taken and showing for purposes of illustration the slate veneer writing surface of my invention 35 as comprised of a plurality of slate pieces jointed together to provide a smooth continuous slate surface and suitably secured to the backing support; and

Figure 5 is a perspective of a drafting board 40 provided with my improved slate veneer writing surface.

One method of making my improved blackboard consists in, first, splitting a rough slate block into sheets thicker than the desired thickness of the final slate veneer. These slate splitting operations are well known in the art. Secondly, I hold the split slate sheet aforementioned to the surface of suitable flat supporting material which acts as a chuck on which the thin split slate sheet 45 can be machined, without any considerable slate breakage, and form the desired veneer surface by machining. Any desired polishing or other finishing of the veneer sheet can also be effected. The finished veneer sheet which is so thin and 50 fragile that it can be handled in material sizes only with difficulty without its breaking under its own weight is then slid upon and secured to, preferably by cementing, a suitable backing-support which forms a body member for the blackboard, one such desirable body member being 55 comprised of plywood 12, Figures 2 and 3, of any desired thickness. Another way of securing the finished veneer sheet to the backing-support consists in spreading cement upon one face of the 60 veneer sheet and pressing the backing support onto said veneer face.

Another method of forming the slate veneer sheet, and combining the same with the backing-support, consists in cementing the split slate 65 sheet to any suitable platen, such as a planing machine bed, using a thermo-cement, such as beeswax or shellac, for this purpose, then planing down the split slate sheet to the veneer thinness, and then reheating so that the veneer can 70 be removed from the platen in finished form.

Then the veneer sheet can be cemented to a suitable backing support to form the final product.

If desired, the final backing-support of the blackboard, such as the plywood 12, can be utilized as the chuck upon which the thin split slate sheet is machined and finished, so that it is then unnecessary to transfer the finished veneer sheet from a chuck base to the final blackboard body. In this event, the thin split slate sheet is firmly secured, as by cement, to the support which acts 10 both as a chuck and a final blackboard body, before the machining and finishing are effected.

For purposes of illustration, the blackboard structure made as described is shown in Figure 1 nailed to a building wall 1. This method of 15 mounting the blackboard 2 is effected by an ordinary nailing operation, and the nails 4 can be freely driven through the slate veneer 3 and the backing-support without injury to the veneer facing.

20 It will be understood, of course, that if the improved slate veneer writing surface is desired upon both sides of the backing-support, the latter can be so provided, and such a showing is presented in Figures 2, 3, and 4, the slate veneer upon one side being a single slate sheet 6, and the slate veneer upon the other side being comprised of a plurality of small sections 13 cemented to the backing-support 12, the edges 14 of adjacent veneer sections 13 being jointed to provide a 30 smooth continuous slate surface. Thus, a plurality of thin split slate sheets can be used, scrap slate if desired, cut to suitable sizes and shapes and machined to the veneer thinness, and secured to the supporting material and jointed to form 35 the complete slate veneer writing surface.

It is well known in the art that the formation of natural slate is such that the sheets thereof obtained by splitting, both the thinnest and the comparatively thick sheets, are not perfectly 40 plane, but are generally curved or bowed. In machining operations, such as I utilize for obtaining my veneer thinness, this curve or bow in the sheets would result in fracturing the sheet, if it were not held closely to the chuck base. However, after the sheet has been machined to the 45 said veneer thinness, the veneer sheet will closely hug the backing-support and will follow the latter so as to conform to its shape and so as to conform to any changes in the shape of the backing-support caused by bending or warping, thus obviating any fracturing or breaking of the veneer sheet by reason of the bending or warping of the 50 backing-support. By so planing the slate pressed against a flat surface, I avoid cutting the slate across the grain of its natural split. Thus, the resulting planed sheet, while its resistance to bending is now very greatly reduced, still conforms with the natural plane of cleavage, with the resulting better writing surface which is 55 incident to this condition. The improved veneer sheet is subject in use to blows upon its veneer facing, but the character of the veneer facing which I provide, in the manner hereinbefore described, is such that even moderate hammer blows thereon will not fracture the slate, but 60 will leave only slight dents therein.

The conference blackboard 5, shown in Figures 2 and 4, is shown, for purposes of illustration, as being mounted upon a suitable standard having 65 the feet 7, the upright stanchions 8, and the strengthening cross frame member 9. The latter serves also as a suitable support for chalk and erasers. The conference blackboard 5 is secured 70 to its supporting frame by clamps 10, the latter 75

having journal portions which are pivotally mounted in the supporting frame, by means of which the blackboard 5 can be swung from side to side and secured in its desired pivotal position 5 through the use of the binding nuts 11.

I illustrate in Figure 5 the application of my invention to a drafting board 15. A suitable working board 16 is provided with a thin slate top surface 17 cemented thereto and suitably machined and polished to form the slate veneer writing surface, and the slate-veneered board maintained at a suitable working height by the supporting pedestal 18.

Although my improved blackboard may be provided with a border frame, for any desired purpose, such as ornamentation, such a border frame is not necessary for the protection or proper functioning of the slate veneer writing surface, or for the mounting of the blackboard. The finished 20 product is a unitary composite article comprised of the backing-support and its natural slate writing surface, having the characteristics of the backing-support, with the exception of the writing surface which retains its superior writing 25 qualities, and can be simply fastened by nails 4 to a building wall 1, such as shown in Figure 1, or clamped to a support, such as shown in Figures 2 and 4, or mounted upon a pedestal, such as shown in Figure 5. Ordinary school slates of 30 sizes suitable for individual use, and requiring no mounting or special support, consist only of a suitable body member having a side or sides provided with the natural slate veneer.

What I claim is:

- 35 1. An improved blackboard consisting of a backing-support having a veneer of natural slate cemented thereto of the order of one-thirty-second inch thickness.
2. An improved product having a natural slate 40 writing surface, comprising a support amenable to bending and warping and having a natural slate veneer facing cemented thereto and conformable to the bending and warping of the support, whereby all parts of the facing permanently 45 hug the support.
3. An improved process of making blackboards consisting in cementing thin split slate material to a suitable base capable of serving as a backing-support, and also serving as a chuck for slate- 50 machining, and then machining the slate mate-

rial to form slate veneer on the base of the order of one-thirty-second inch thickness.

4. An improved blackboard consisting of a bendable and warpable support and a thin natural slate sheet secured thereto having the said characteristics of the support. 5

5. An improved blackboard consisting of a backing-support having a facing of natural slate secured thereto, said facing being in the nature of a veneer not exceeding one-sixteenth inch 10 thickness.

6. An improved blackboard consisting of a composite structure comprised of superimposed united layers of natural slate and slate-supporting material, the slate being of such a thinness that its natural toughness predominates over its natural brittleness, whereby it is amenable, without fracturing or splitting, to any reasonable bending and warping. 15

7. An improved blackboard consisting of a tough, fracture-resistant backing-support and a machined writing surface secured thereto and comprised of a plurality of edge-jointed natural slate sections, said slate sections being of a thinness sufficient to partake of said characteristics 20 of the support. 25

8. An improved process of making blackboards consisting in securing a sheet of natural slate throughout its area to a deformable support, and then machining the slate sheet to a thinness at 30 which it will follow the deformations of the support without cracking or splitting.

9. An improved process of making a slate blackboard surface consisting in positively holding a natural-split natural slate sheet tightly against the machining area of a support, and then machining the slate sheet to a thinness at 35 which it per se will hug the support.

10. An improved process of making a slate blackboard surface consisting in positively holding a natural-split natural slate sheet tightly relatively to the machining area of a support so that subsequent machining of the slate sheet will be on its plane of cleavage, or substantially so, 40 whereby said machining will cross the plane of cleavage but slightly if at all, and then machining the slate sheet to a thinness at which it per se 45 will hug the support.

RALPH W. SHENTON. 50
